UNITED STATES PATENT OFFICE.

JOHN F. CARPMILL, OF NEW BRITAIN, CONNECTICUT, ASSIGNOR TO NORTH & JUDD
MANUFACTURING COMPANY, OF NEW BRITAIN, CONNECTICUT.

BELT BUCKLE.

Application filed July 7, 1927. Serial No. 204,072.

This invention is a belt buckle having means for retaining the loose end of the belt, the object being to provide a light and inexpensive buckle of such construction that the loose end of the belt may be easily tucked behind the retaining element. The invention is illustrated in the accompanying drawing and will be hereinafter fully described, the novel features being particularly pointed out in the appended claims.

In the drawing, Figure 1 is a front elevation of the improved buckle;

Figure 2 is a rear elevation of the same;

Figure 3 is a longitudinal section showing the manner of connecting a belt or strap to the buckle;

Figure 4 is a detail perspective view of the buckle.

The buckle comprises a front member and a back member each stamped from a single sheet metal blank. The front member comprises top and bottom bars 1 connected by the end bars 2 and 3 and having wings 4 extending from their rear faces. The end bar 2 is disposed approximately within the plane of the top and bottom bars 1 but is slightly inclined, its inner edge being just back of or at the rear faces of the bars 1 and its outer edge being flush with the front faces of the same and constructed with teeth 5. The end bar 3 is flat but is offset at its ends, as at 6, whereby it is disposed in spaced relation to the front of the buckle, and parallel with the bar 3 is a loop bar 7 which is offset forwardly from the front of the buckle and is connected therewith by the end webs 8, as shown. The back member of the buckle is an open rectangular plate 9 fitting between the wings or flanges 4 and provided at its inner end with the forwardly projecting lugs or ears 10 pivotally engaged upon a pintle 11 secured in and extending between the wings 4. At the outer end of the back plate is a forwardly projecting lip 12 which is adapted to lie in proximity to the teeth 5 when the back plate is swung forwardly.

The fast or anchoring end 13 of the strap is looped around the pintle 11 and the inner end of the back plate 9 and secured by stitching or otherwise fastening the extremity of the strap to the main length thereof. The free end 14 of the strap is passed back of the lip 12 and then forward through the back plate to pass between the lip and the bar 2, thence across

said bar 2 and under the loop bar 7, as shown in Fig. 3. The tension in the strap exerts a pull upon the lip 12 which causes it to approach the bar 2 and press the strap against the teeth 5 whereby it will be firmly held. It will be noted that the front of the buckle is open and the free extremity of the strap or belt may, therefore, be easily engaged behind the loop bar 7 and passed over the end bar 3. When the strap is to be released, its free end is withdrawn from the loop bar and then swung across the edge of the lip 12 whereupon the lip will move away from the toothed end bar 2 and free the strap. By referring particularly to Fig. 3, it will be noted that no free part of the buckle projects beyond the front or free end of the belt or strap and said end is held straight or flat and retained by the loop or end-retaining bar which is located between the ends of the buckle. It will also be noted that the lip 12 does not project past the toothed bar but terminates short thereof so that the strap is positively engaged and held by and between the edge of the lip and the bar.

Having fully described my invention what I claim as new and desire to secure by Letters-Patent, is:—

1. A belt buckle consisting of an open front member having one end bar provided with teeth on its outer edge, a retaining bar near the opposite end bar of the member and offset from the front face thereof, and a back member pivotally mounted on the front member and having a forwardly projecting lip at its free end adapted to hold a belt to the teeth on the end bar of the front member.

2. A belt buckle consisting of a front member having a toothed bar at one end, a bar adjacent to the opposite end offset forwardly from the front face of the member, and a loop bar adjacent the second-mentioned bar and between the two end bars and offset rearwardly from the front face of the member, and a back member pivotally mounted on the front member and having a lip at its free end adapted to lie in proximity to the toothed bar on the front member and also having an opening adjacent the pivot through which a belt may pass, the lip terminating short of the toothed bar whereby the strap will be positively engaged and held by and between the edge of the lip and the teeth of the bar.

3. A belt buckle including a back member

formed of an open frame having at one end forwardly projecting ears, and at its opposite end a forwardly projecting lip, a front member formed of an open frame having rearwardly projecting ears, end bars and an intermediate belt-end retaining bar, means pivotally connecting said ears of the back and

front members, one of the end bars having teeth arranged in close proximity to said lip, and both end bars being arranged rearwardly of the belt-retaining bar. 10

In testimony whereof, I have signed this specification.

JOHN F. CARPMILL.
